A. HOLLANDER

SCREW PUMP

Filed March 27, 1924

FIG. 1

FIG. 2

INVENTOR.

Aladar Hollander

BY

Miller, Henry & Boykin
ATTORNEY.

UNITED STATES PATENT OFFICE.

ALADAR HOLLANDER, OF BERKELEY, CALIFORNIA.

SCREW PUMP.

Application filed March 27, 1924. Serial No. 702,241.

To all whom it may concern:

Be it known that I, ALADAR HOLLANDER, a citizen of the United States, and resident of the city of Berkeley, county of Alameda, State of California, have invented new and useful Improvements in Screw Pumps, of which the following is a specification.

My invention is particularly applicable to what is known as screw pumps wherein a zone of increased pressure is established on one side by an impeller having blades with an axial pitch and substantially devoid of radial pitch.

It has heretofore been found that when the resulting increased pressure is exposed to the bearings of the rotating shaft in such a pump it has been difficult to maintain lubrication because the tendency of the pump fluid to force its way between the bearings and shaft.

My invention has for its object the prevention of the bad effects of pressure water between the bearings and shaft of such a pump, and securing the proper lubrication of said shaft and bearings at all times.

Other objects will appear from the drawings and specifications which follow:

These objects I accomplish by employing in the hub of the impeller a plurality of vanes adapted to force outward by centrifugal action, any water or fluid which would otherwise find its way into the bearings.

By referring to the accompanying drawings and specifications my invention will be made clear.

Fig. 1 is a cross section through a vertical type of screw pump to which my invention has been applied.

Fig. 2 is a plan view of the screw impeller of Fig. 1 to which my invention has been applied.

Throughout the figures similar numerals refer to identical parts.

An inlet thimble for the pump is shown by the numeral 1, and a discharge outlet is shown at 2. At 3, 4, 5 and 6 are shown blades of the impeller having any suitable

axial pitch adapted to establish the requisite pressure to discharge through the outlet 2 fluid received in the direction of the arrow 7. At 8 is a running joint between the hub 9 of the impeller and the stationary casing member 10, and the water from the pressure side of this impeller would, were it not for my invention, find its way into the passage 13. To overcome this tendency of the water to enter I core out the hub of the impeller, casting therein a plurality of pump vanes as 14, 15, which function upon the rotation of the impeller to throw outwardly and maintain clear of the bearings 11, 13 and journals 16, 17, any water from the pressure side of the pump. The action of these vanes will be such that there is a partial vacuum formed in the channel 8 whereby lubricant is permitted to slowly advance down the sleeve 12 finding its way, a drop at a time, and when its lubricating qualities have been expended discharges into the channel 8 and thence through the discharge 2. This lubricant may be fed from the cup 20 through the bearing sleeve channel 21 thus maintaining a perfect lubrication of the bearing and journal 13, 17 respectively and maintaining a supply of lubricant in the sleeve 12 to feed the bearing and journal 11 and 16 respectively as required and during the pump operation.

I claim:

In a pump, a screw type impeller, a shaft adapted to drive said impeller, a casing having a bearing for said shaft adjacent the discharge side of said impeller, an annular pocket having spiral vanes therein in said impeller open on the discharge side and closed on the suction side of said impeller, said casing closing the said open side of said pocket and forming a running joint with the impeller whereby the rotation of the impeller establishes a pressure from the pocket and through the running joint greater than the pressure of discharge of the impeller.

ALADAR HOLLANDER.
